UNITED STATES PATENT OFFICE.

WILLIAM WOODCOCK, OF ELIZABETH, NEW JERSEY.

METALLIC BRAKE-BEAM.

SPECIFICATION forming part of Letters Patent No. 276,122, dated April 17, 1883.

Application filed February 12, 1883. (No model.)

To all whom it may concern:

Be it known that I, WILLIAM WOODCOCK, a citizen of the United States, and a resident of Elizabeth, Union county, New Jersey, have 5 invented certain Improvements in Brake-Beams, of which the following is a specification.

My invention consists of an improvement, fully described hereinafter, in the metal brake-beam for which Letters Patent No. 270,871 were granted to me on the 16th day of January, 1883.

In the accompanying drawings, Figure 1 is an edge view of my improved brake-beam; 15 Fig. 2, a plan view; Fig. 3, a view of a brake-shoe, and Fig. 4 a modification of part of the beam.

In my former patent I described and claimed a brake-beam in which two wrought-iron bars, 20 placed flatwise one above the other and welded together at and near their opposite ends, were combined with and secured to a central filling-block, by which the bars were separated in the middle, said bars converging toward the opposite ends.

I have found that a more economical and substantial beam, possessing the advantages due to the placing of two bars flatwise one above the other and converging toward the 30 opposite ends, can be made by casting the beam in one piece, the casting being either of steel or of cast-iron rendered malleable.

The two bars A A, Figs. 1 and 2, and the

solid end portions, *a a*, are cast in one piece with the central portion, *b*, through which extends a horizontal opening, *n*, for receiving the stem of the forked bar *M*, which carries the pin of the brake-lever, the stem being threaded and provided with suitable nuts. The bars A A are made on a slight taper from the middle to the opposite ends; but they may be made of a uniform width throughout. Each of the solid ends *a a* may be notched at *e* to receive a key, by which a brake-shoe (shown in Fig. 3) is secured to the beam; or each solid end may 45 have an eye, *x*, Fig. 4, for receiving a bolt by which a brake-shoe may be attached to the beam.

I prefer to make the beam of cast-steel; but it may be made of cast-iron converted into malleable iron by the usual process.

I claim as my invention—

The within-described cast-steel or malleable-iron brake-beam, the same consisting of bars A A, placed flatwise one above the other and 55 united at and near the opposite ends, and the central portion, *b*, all being cast in one piece, as set forth.

In testimony whereof I have signed my name to this specification in the presence of two sub- 60 scribing witnesses.

WM. WOODCOCK.
